UNITED STATES PATENT OFFICE.

SVEND E. JOHANNESSEN, OF PITTSFIELD, MASSACHUSETTS, ASSIGNEE TO GENERAL ELECTRIC COMPANY, A CORPORATION OF NEW YORK.

ALTERNATING-CURRENT REGULATOR.

1,088,704.

Specification of Letters Patent.

Patented Mar. 3, 1914.

Application filed September 16, 1909. Serial No. 517,968.

To all whom it may concern:

Be it known that I, SVEND E. JOHANNESSEN, a citizen of the United States, residing at Pittsfield, county of Berkshire, State of Massachusetts, have invented certain new and useful Improvements in Alternating-Current Regulators, of which the following is a specification.

My invention relates to alternating-current regulators, and more specifically to that type of regulators which are used for regulating the current supplied to arc lamps, and has for its object an improvement in such devices.

More specifically, my invention relates to regulators which are used for regulating the illumination for the lamps of moving picture machines. In many machines of this class arc lamps are used and the illumination which they produce depends upon the amount of current consumed by the lamp. Furthermore, arc lamps are of low voltage and the circuits from which they are supplied are usually of a much higher voltage. Regulators for these lamps, therefore, must be able to supply a variable current to the lamp, which current must usually be of a lower voltage than that of the supply circuit and the voltage of this current must be kept of approximately the same value, since the electro-motive force of an arc is a substantially constant quantity.

In the past, regulation has been obtained in certain instances by the use of a transformer or compensator with reactance coils connected in series with the lamp. Regulators of this construction, however, are subject to considerable heat losses in the reactance coils used, and the object of my invention is to minimize these losses as far as possible and construct an apparatus cheaper than those in use at the present and one that shall be simple and reliable in character.

I accomplish the object of my invention by combining the reactance coils and the transformer into one structure, winding the reactance coils upon the same core as and in inductive relation to the primary transformer winding. The reactance coils are connected in series with the secondary of the transformer and a portion of the reactance coils is so connected that the electromotive force induced in it will oppose the flow of current, the remainder being

connected in a reverse direction. By this construction I am enabled to effect a considerable saving in heating. By placing the reactance coils upon the same core and in inductive relation to the primary winding these coils are influenced by the main transformer flux. Therefore to produce a given reactance not so much leakage flux is required as if the reactance coils were on a separate core magnetized by the current flowing in them. It is not necessary to magnetize this separate core. This I have found saves considerably in the heating. I further save in that by causing the current to flow in a portion of the reactance in a direction reverse to that of its electromotive force induced by the primary winding. I am enabled to obtain the desired reactance with still less leakage flux.

Considered in another aspect my invention consists in the construction of a special form of transformer with auxiliary windings which give increased reactance connected in series with the secondary winding. These auxiliary windings, as explained above, are in inductive relation to the primary winding and are connected so that their induced voltages are in opposition. By the use of two such windings having substantially equal voltages induced therein, it will be obvious that the ratio of transformation of the transformer will be unaffected by connecting these windings in series with the secondary circuit.

In order to obtain different current values for the lamp or other translating devices to which my regulator is connected, I employ a special form of switch for connecting different amounts of the reactance coils in the secondary circuit. This switch and the connections between it and the reactance coils are so arranged that during the movement of the switch to vary the amount of current, the secondary circuit will not be opened, and when portions only of the reactance coils are used these portions will be connected so that their voltages are in opposition. Since the reactance coils have voltages induced therein, it will be obvious to those skilled in the art that in changing the secondary circuit connection so that a whole or a part of the reactance coils are included therein, without interrupting the circuit, a portion of these coils will be short circuited and therefore a heavy

- current will flow in them, unless means are used to prevent this occurring. A means commonly used is the so-called "preventive resistance" which is a resistance so arranged that upon the movement of a switch the portion of a coil having a voltage induced therein is short circuited through this resistance and the current flowing therein is thereby limited in value.
- 10 By the special form of switch and connections which I employ, I am enabled to limit this short circuited current without using a preventive resistance, and I accomplish this result by so arranging the connections that the switch is passing from one position to another will not short circuit upon themselves portions of the reactance coils but will connect portions of these coils with their voltages opposed in series, so 20 that the current flowing in them will be substantially *nil*.

For a further understanding of my invention, reference may be had to the accompanying drawings where—

- 25 Figure 1 shows in perspective an external view of my regulator; Figs. 2 and 3 show on a larger scale portions of the switch mechanism; Fig. 4 shows, diagrammatically, the windings and arrangement of 30 connections; and Figs. 5, 5^a, 6, 6^a and 7 show connections for various positions of the switch.

Referring first to Fig. 1, 1 is a base on which the various portions of the apparatus 35 may be mounted; 2 is a casing which surrounds the core and windings of the transformer; 3 is an insulated portion of the switch mechanism attached to the casing; 4 is a movable switch blade which is arranged to be in operative relation with stationary contacts 5 attached to 3; and 6 are terminals of the transformer windings.

Referring to Fig. 2, the movable portion 45 of the switch consists of a blade 7 which may be pivoted at one end in the usual manner so that the blade will move in a vertical plane. At the top of the blade are insulating members 8 and surrounding the edges of members 8 are conducting members 9 so arranged that there will be a considerable portion of insulation between these conducting members. 10 is the usual handle for the operation of the blade.

Referring now to Fig. 3, this figure shows 55 the stationary contacts which are made of substantially C shaped members, the ends of these members making contact with members 9 on the movable blade, the centers of these members having lugs 12, by which 60 they are attached to the insulating member 3 on the top of the casing and connected to the transformer windings.

Referring now to Fig. 4, the regulator is shown as consisting of a magnetic core 13 65 having two legs joined by suitable end

pieces. This core may be made up in the usual manner of laminated punchings. Surrounding one leg of the core is shown the primary winding 14, 14', which is shown as made of two portions so arranged that they 70 may be connected in series or in parallel in the usual manner for connection with supply circuits of different voltage. The ends of these windings are shown as connected to terminals 6. Surrounding the second leg of the core is shown the secondary winding which consists of two portions 15 and 15', the outside ends being connected to terminals 16, to which may be connected suitable translating devices, which are not 80 shown.

In addition to the primary and secondary windings are the reactance coils, which I shall call for convenience auxiliary windings, the one, 17, being wound on the leg of 85 the core surrounded by the primary winding 14, and the other, 18, being wound on the other leg of the core. These auxiliary windings which are used for the purpose of obtaining reactance are wound to have induced voltages of substantially equal value 90 at some degree of load, and are provided with intermediate taps 17' and 18' so that the amount of the coils in series with the secondary winding and thus the amount of 95 reactance in series with this winding may be varied. The terminals and intermediate taps of these auxiliary windings are connected to the stationary clips 5 of the switch mechanism and the inside ends of the secondary winding 15 and 15' are also connected to these clips.

While I have shown the windings as arranged separately upon the legs of the core, it is not necessary that they should be 105 wound in this fashion and they are shown as so wound merely for the purpose of clearness of illustration. Actually, in one practical construction, the primary winding is wound on one leg of a rectangular core, 110 and the secondary winding is wound on the other leg, the auxiliary winding 17 being located under the primary and the auxiliary 115 18 under the secondary winding or the windings may be arranged in any of the usual manners which will suggest themselves to those skilled in the art.

For an understanding of the operation of the regulator, reference may be had to the remaining figures which show the connections of the secondary circuit for various positions of the switch mechanism. Referring first to Fig. 5, this figure shows the connection for the maximum current of the secondary, the connection which exists when 125 the movable blade of the switch is in the position shown in full lines in Fig. 4. With this connection it will be seen that the two secondary coils are in series and the auxiliary reactance coils are not in the circuit. 130

If, now, it be desired to decrease the amount of current the switch may be moved to the right, as shown in Fig. 4, until it first comes in contact with the middle pair of clips. This will be an intermediate position and the connections existing with this position are shown in Fig. 5^a. The movable blade of the switch has not been illustrated in this intermediate position but it has been illustrated as shown by the dotted lines in Fig. 4 for the second intermediate position where the contact members on the switch blade make contact between both the middle pair of clips and the pair of clips on the extreme right.

It will be seen that in the intermediate position of the switch blade, contact is made between a succeeding pair of clips before contact is broken between the clips which the switch blade is leaving. This prevents the switch from opening the circuit in passing from one position to another, and by the peculiar circuit connections employed avoids any difficulty in changing from one position to another. The manner in which this is done will be best understood by referring to Fig. 5^a. When the blade is in this intermediate position it will be seen that the two portions of the secondary winding are in series, and connected thereto at points 19 and 20 are portions of the auxiliary windings 17 and 18. It will be further seen that the portions of the auxiliary windings connected to the secondary circuits are short circuited upon themselves. These windings are, however, so arranged and connected that the induced voltages of the two windings will be in the direction, for example, as that shown by the dotted arrows; that is, these voltages will be in opposition, and thus a very small, if any, current will flow. The instantaneous flow of current in the secondary circuit may be shown by the arrows which are not dotted.

When the movable blade is moved from the intermediate position to the second position, it breaks the connection between points 19 and 20 and the connections will be those shown in Fig. 6. This connection gives a medium value for the secondary current and it will be seen that the two portions of the secondary winding are connected in series and in series with a portion of each of the auxiliary windings, these portions being also connected in series. The direction of the instantaneous flow of current at any time may be shown by the arrows in full line and the direction of the instantaneous induced voltages in the reactance coils may be shown by the dotted arrows. It will thus be seen that the auxiliary windings are wound and connected so that their induced voltages are in opposition or "buck each other", and it will also be seen that the current is made to flow in the coil 17 in a direction opposite to that in which its induced voltage

would tend to make it flow but the current flows in the coil 18 in the same direction as that in which its induced voltage would tend to make it flow.

Referring now to Figs. 6^a and 7, these figures show the connections for the second intermediate position and the final position of the movable switch blade, the final position giving the lowest magnitude of current, the entire coils 17 and 18 being connected in series with the secondary windings, as will be seen from Fig. 7. In the intermediate position, as shown in Fig. 6^a, the instantaneous direction of the current may be assumed to be that of the full line arrows and the instantaneous induced voltages in the reactance coils may be assumed to be in the direction shown by the dotted arrows. It will be seen that the two portions of the reactance coils which are short circuited will have their voltages in opposition and thus an excessive flow of current will be prevented as described for the first intermediate position.

While I have shown and described a preferred embodiment of my invention, I do not limit myself to this embodiment, but seek in the appended claims to cover all embodiments which will be obvious to those skilled in the art and will not depart from the spirit of my invention.

What I claim as new and desire to secure by Letters Patent of the United States, is,—

1. In an electrical apparatus, a winding and a reactance in series therewith comprising a plurality of coils adapted to have voltages induced therein, the coils being so connected to the winding that their induced voltages are in opposition.

2. In an electrical apparatus, a winding and a reactance in series therewith comprising two coils adapted to have voltages induced therein, the coils being so connected to the winding that their voltages oppose each other.

3. In an electrical apparatus, a winding and a reactance in series therewith comprising two coils adapted to have substantially equal voltages induced therein, the coils being so connected that their voltages are in opposition.

4. The combination in an electrical apparatus of a magnetic core, an inducing winding surrounding the core, a second winding in inductive relation to the first winding, and a plurality of coils in inductive relation to the first winding connected to the second winding so that the voltages of the coils are in opposition, the various inductive relations of the coils to the first winding differing relatively.

5. The combination in an electrical apparatus of a magnetic core, an inducing winding surrounding the core, a second winding also surrounding the core in inductive relation to the first winding, and a reactance

- comprising two coils in inductive relation to the first winding connected in series to each other so that their induced voltages are in opposition and connected in series with one of the windings. 5
6. The combination in an electrical apparatus of a magnetic core, an inducing winding surrounding the core, a second winding also surrounding the core in inductive relation to the first winding, a reactance comprising two coils in inductive relation to the first winding connected in series so that their induced voltages are in opposition and connected in series to one of the windings, and 10 means for varying the amount of the coils connected in series to the winding. 15
7. The combination in an electrical apparatus of a magnetic core, an inducing winding surrounding the core, a second winding also surrounding the core in inductive relation to the first winding, a reactance comprising two coils having intermediate taps, and a switch adapted to connect the coils in series with their induced voltages in opposition in series with the second winding, and 20 to alter the amount of the coils in series with the second winding. 25
8. The combination in an electrical apparatus of a two legged magnetic core, a primary winding surrounding one leg of the core, a secondary winding wound in two sections surrounding the other leg of the core, reactance coils having intermediate taps surrounding each leg of the core, and a switch 30 adapted to connect the secondary windings in series and in series with the reactance coils so that the induced voltages of the coils are in opposition, and to vary the taps through which the coils are connected. 35
9. In an electrical apparatus, a reactance comprising two coils having voltages induced therein and intermediate taps, and a switch adapted to connect the whole or portions of the coils in series with their voltages 40 in opposition by varying the taps to which it is connected without opening the circuit in passing from one tap to another, the connections between the taps and the switch being so made that the switch in passing from 45 one tap to another connects the portions of the coils between successive taps in parallel with their voltages in opposition. 50
10. In an electrical apparatus, a winding, a reactance comprising two coils adapted to
- have voltages induced therein and intermediate taps, and a switch adapted to connect the coils in series with their voltages in opposition and in series with the winding, and to vary the taps through which the coils are connected without opening the circuit, the 55 connections between the taps and the switch being so made that the switch in passing from one tap to another connects the portions of the coils between successive taps in parallel with their voltages in opposition. 60
11. The combination in an electrical apparatus of a two legged magnetic core, a primary winding surrounding one leg of the core, a secondary winding wound in two sections surrounding the other leg of the core, reactance coils having intermediate taps surrounding each leg of the core, a switch comprising a movable blade having contact members at each edge and an insulating member between, and a plurality of pairs 70 of stationary clips in operative relation to the blade, connections between the stationary clips the secondary windings and the reactance coils so made that the switch in its movement connects the secondary windings 75 in series and in series with a whole or part of the reactance coils connected so that their voltages are in opposition. 80
12. A transformer having a plurality of coils wound on the main core in different inductive relations to the primary winding and connected to the secondary winding of the transformer in such a manner that the voltages generated 85 in the coils are in opposition. 90
13. A transformer having two coils wound on the main core in different inductive relations to the primary winding and connected to the secondary winding of the transformer in such a manner that the voltages generated in the coils are in opposition. 95
14. A transformer having two coils wound on the main core in different inductive relations to the primary winding and connected to the secondary winding of the transformer in such a manner that the voltages generated 100 in the coils are substantially equal and are in opposition.

In witness whereof, I have hereunto set my hand this third day of September, 1909.

SVEND E. JOHANNESEN.
